(57) **CLAIM**

I claim the ornamental design for a cellular phone carrying case with an inner pouch, as shown and described.

DESCRIPTION

FIG. 1 is a perspective view of a cellular phone carrying case with an inner pouch showing my new design.

FIG. 2 is a front plan view of the cellular phone carrying case with an inner pouch of my new design.

FIG. 3 is a rear plan view of the cellular phone carrying case with an inner pouch of my new design.

FIG. 4 is a top plan view of the cellular phone carrying case with an inner pouch of my new design.

FIG. 5 is a bottom plan view of the cellular phone carrying case with an inner pouch of my new design.

FIG. 6 is a right side plan view of the cellular phone carrying case with an inner pouch of my new design; and,

FIG. 7 is a left side plan view of the cellular phone carrying case with an inner pouch of my new design.
